ABSTRACT OF THE DISCLOSURE

An initial potential energy is stored within a resilient power reed as deflected by the high energizing of an electromagnet. When the magnet is caused to be deenergized, the reed is released and will resonate at its natural frequency to provide the power for operating a printing head. Circuitry means responding to a deenergizing signal to the magnet is timed to act when kinetic energy in the return oscillation of the reed is at substantially zero and at lower energy will reenergize the magnet to complete the return movement of the reed and restore full potential energy therein.

BACKGROUND OF THE INVENTION

The invention relates to improvement in data printout devices and more particularly to novel power means for operating a unitary printing head, upon which all letters, numerals and symbols are arranged and which is shiftable step by step in either direction along a nonshiftable work support platen, to effect a printing in the form of intelligible words, numbers and operation symbols as received in the form of electronic impulses from well-known data processing machines. The printer may thus be used to record data on ledgers, checks, invoices, bills or any other type of record media which may be accommodated upon the work support platen.

Such known printing type heads are usually powered by cyclically driven mechanical devices for effecting the printing stroke thereof. Also, printing may be effected heretofore upon the energizing of an electromagnet by an electronic impulse signal as received from a control machine.

SUMMARY

Overall output of present day computers is frequently slowed up where printout operations are desired.

Cyclically driven mechanical means for printing are not only slow of operation but are both cumbersome and costly. Also, known energizing of electromagnetic means whereby to effect printing requires substantially large power magnets, which are not only more costly but require longer buildup time for energizing and thus slows up any printing operation.

To obtain faster printing operations with reduced size magnets having lower input energy requirements, the present invention first stores potential energy within a power reed limiting each operation to a single oscillation. Thereafter, in lieu of being energized, the magnet may be deenergized to immediately permit the reed to operate the printing means. Consequently, any buildup time for reenergizing the magnet may now be timed to coincide with a subsequent return stroke operation of the printing means.

An object of the present invention is to provide an improved power means for operating a printing head, which power means is more rapid in responding to an impulse control signal and will increase operating speed of the printing head.

Another object is to provide such power means capable of inherently completing an initiated printing operation within a given predetermined fixed time interval.

Another object provides for minimizing size and power

requirements of the electromagnets controlling operation of the printing head.

As another object, the invention provides for an improved power train connecting the printing head with said power means, whereby printing operations may be effected with the printing head displaced to any tabulated position.

A further object is to provide a power means which is inherently capable of minimizing shock within the printing power train.

10 The foregoing and other objects, features and advantages will be more apparent from the following more particular description of the preferred embodiment of the invention as illustrated in the accompanying drawings, wherein;

BRIEF DESCRIPTION OF THE DRAWINGS

FIGS. 1-1A jointly show a front elevation of the machine embodying the invention.

FIG. 2 is a left side elevational view of the machine.
20 FIG. 3 is a plan view of the power reed and associated magnets as viewed along line 3—3 of FIG. 2.

FIG. 4 is a right side elevation of the printing unit.
FIG. 5 is a top sectional view taken along the line 5—5 of FIG. 4.

25 FIG. 6 is a plan view of the printing unit.
FIG. 7 is a cross section elevation of the same taken on line 7—7 of FIG. 6.

FIG. 8 is an enlarged fragmentary plan view of the printing drum and aligner means therefor.

30 FIGS. 9-9A and 10 are graphic illustrations of an operation of the power device.

DESCRIPTION OF THE PREFERRED EMBODIMENT

35 Referring now in particular to FIGS. 1-1A, the machine embodying the present invention comprises left and right side frames 1 and 2 having supported for rotation therein a non-shiftable work support platen 3. Forwardly within said side frames is secured a transverse rod 4, while rearwardly of rod 4 said frames support a rail 5, which together serve to support for transverse movement a shiftable carriage C having mounted thereon the character printing drum 6, as hereinafter described.

Secured to the left side of said carriage by means of stud 7 is a flexible steel tape 8 which passes first around a pulley wheel 9 pivotally mounted upon a bracket 10 fast to the left side frame 1, then across the front of the machine and around a pulley wheel 11 rotatably supported upon bracket 12 secured to the right side frame 2, and subsequently is wound upon the drum 13 fast to the shaft 14 of a stepping motor 15. Fast also to motor shaft 14 is a second drum 16 on which is wound a similar tape 17, which passes around a pulley wheel 18 and is secured to the right side of the printing carriage C by means of stud 19. Thus in accordance with certain selective impulse signals, as received from any suitable control source or computer means in the well-known manner, motor 15 serves to displace printing carriage C selective distances either to the right or to the left.

60 Printing carriage C comprises a support frame 20 (FIGS. 4-7) the forward end of which is slidably upon the rod 4 and the rearward end having rollers 21 for riding along the rail 5. Frame 20 is provided with a pair of upwardly extending trunnions 22 for receiving the pivot studs 23 fast within the bifurcated arms 24' forming the lower end of a U-shaped frame 24. Within the upper arm 24" of said frame is bearinged for rotation the upper portion of a shaft 25 upon which is fast the character or printing drum 6. If desired, drum 6 and shaft 25 may be a single piece, for instance, of molded nylon material. The lower end of shaft 25 is enlarged to form a socket for receiving the ball-shaped end 26 of a shaft 27 extending

upwardly from a stepping motor 28 supported to the underside of the printing carriage frame 20. A pin 29 extends through ball 26 and is received by an elongated vertical slot 30 in the lower end of the printing drum shaft 25, whereby to effect drive connection thereof with the motor shaft 27 in manner to permit an upward and downward movement of the printing drum.

To effect upward and downward movement of the printing drum, a pair of spaced rearwardly extending levers 31 are each pivotally mounted at 32 upon an upwardly extending portion 20' of the carriage frame 20. The rearward ends of each lever 31 are bifurcated to embrace the top and bottom sides of an enlarged circular disc 33, comprising a shoulder on the shaft 25. Mounted to extend between the pair of arms 31 for movement therewith, is a metal block 34 which with said arms serves as an armature between two opposed magnets 35, 36 supported upon the frame portion 20' of the printing carriage C. With both said magnets in their deenergized condition, a pair of balanced springs 37-37' will act to hold levers 31 and thereby the printing drum 6 at substantially a midpoint position relative to bringing one or the other of two rows of printing characters arranged around the circumference of drum 6 to the printing line with respect to platen 3. It is intended, however, that either magnet shall remain normally energized in accordance with any previous final impulse signal transmitted thereto from the known input devices.

It will be apparent from the above, therefore, that upon simultaneously deenergizing either one of said magnets while energizing the other in accordance with a selected impulse signal, armature 34 will move either upwardly or downwardly until stopped by the particular magnet that becomes energized. Thus the lever 31 is rocked either clockwise or counterclockwise about point 32 in accordance with such impulse signals, and will raise or lower shaft 25 with printing head 6 to selectively bring either row of printing characters thereon into printing alignment with the work support platen 3.

It will be noted that in such operations, potential energy provided in one of the opposed springs 37-37' will decrease while that of the other spring will increase, with the result that lever 31 with armature 34 is caused to be spring biased for either direction of its movement.

This arrangement of spring balancing and with providing caps 38 of suitable antimagnetic material, such as tetrafluoroethylene, upon the core of each magnet serves to provide for a more rapid response of the above devices to any said input impulse signals thereto.

A selection of any desired character to be printed is effected through selective forward or reverse operations of stepping motor 28 to adjust drum 6 from any last previous character selection position to any other character position according to the particular input signals received thereto from the master control devices.

The novel means for effecting a fore and aft printing stroke movement of the printing character drum 6 will now be described.

Rotatably mounted upon a pair of spaced studs 40, 41 fast to the frame 20 of the shiftable carriage C are pulley wheels 42, 43, respectively. Guided between the trunnion arms 22 supporting the pivoted rock frame 24, upon which is mounted the printing drum 6, is a slide block 44 having a pair of spaced shoulders 45, 46 extending rearwardly of cooperating spaced arms 47, 48 depending downwardly from said rock frame 24. An elongated notch 49 in block 44 permits said block to straddle the motor shaft 27, while a rod 50, mounted between the shoulders 45, 46 has one end of a spring 51 secured thereto. The other end of spring 51 is secured to a stud 52 fast within frame 20 and serves to bias block 44 rearwardly. A pair of springs 61, each at one end, being connected to the related arm 47, 48, respectively, and at their other end to a rod 62, held in a suitable notch in the rearward face of shoulders 45, 46 serves to yieldably bias said arms against the forward surface of said shoulders. The forward end of block 44 is

bifurcated to form upper and lower bearing support for a shaft 53 upon which is mounted for rotation between said supports a pulley wheel 54.

With reference to FIGS. 1-1A, a flexible steel tape 55 is secured by stud 56 to the fixed bracket 12 of the machine and extends leftwardly, around the forward surface of pulley wheel 43, thereafter rearwardly around the pulley 54, forwardly around pulley 42 and again leftwardly to pass around a stationary pulley 57 and thence is secured at its opposite end to the distal end of a resilient reed 58 (FIGS. 2 and 3), having the opposite end thereof fast to the base plate 59. Said reed comprises the armature member for a pair of parallel electromagnets 60 fast to the base plate 59, and is designed to effect a printing operation of the drum in the following manner.

Assuming power has been turned on in the machine with the result that magnets 60 are thus energized, reed 58 is now deflected and held by said magnets so that tape 55 will be in a released condition. This permits spring 51 to hold slide block 44 with pulley 54 in a rearward position, thereby taking up any slack which would be imparted to tape 55 by said deflection of reed 58. At this same time, springs 61 will cause frame 24 with printing head 6 to be held in a counterclockwise position.

Magnets 60 may thereafter be deenergized and reenergized according to an established impulse repetition rate as transmitted thereto from any well-known control devices. So that any residual magnetism in magnets 60 will not delay a release of the reed 58, the side of said reed towards magnets 60 is covered with a suitable antimagnetic substance, such as for instance, tetrafluoroethylene. Upon a deenergizing of magnets 60, reed 58 is released and will impart a leftward movement (FIG. 1) to the tape 55. The opposite end of tape 55 being held, as earlier described, it will be obvious that pulley 54 will be moved forwardly, being leftwardly as shown in FIGS. 5 and 6 and will move slide block 44 therewith to impart thereby a rapid clockwise rotation to the frame 24 and printing head 6. During such operation, reed 58 reaches its maximum velocity and will then decelerate in characteristic manner. However, tape 55 will only pull slide block 44 partly forward, thereafter acceleration imparted thereby to frame 24 and printing head 6 will cause the printing head to continue onward and strike the usual type ribbon 63 for effecting printing upon any record form as interposed between said ribbon and the support platen 3. During this latter portion of the printing stroke, it is noted that the deceleration of reed 58 slows motion of slide block 44 and the printing head is permitted to strike freely, so that no printing impact is transmitted back to the tape, thereby avoiding damage to the tape.

On the return stroke of the oscillation of reed 58, tape 55 is caused to be relaxed, permitting spring 51 to return slide block 44 rearwardly, while springs 61, as aided by rebound of the parts and by increased energy stored therein during the printing stroke, restores frame 24 and printing head 6 counterclockwise to normal position.

From the above therefore, it will be noted that because reed 58 acts like a leaf spring, it tends to resonate but is restricted to one cycle, that is, it leaves the magnets 60 as said magnets are deenergized and pulls tape 55 on a forward stroke, or away from the magnets. On the return stroke of the reed 58, in completing the cycle, said reed is recaptured by magnets 60 when energized, as hereinafter described, by a control circuit applied to said magnets at a given time before the reed has fully returned and which builds up the magnetic field sufficiently to pull reed 58 a remaining short distance to normal, whereby the associated parts operated by tape 55 also return to normal, with a minimum of chatter or rebound.

To further understand certain operations and advantages of applicant's novel devices, reference is made to the graphic illustrations shown in FIGS. 9, 9A and 10, which will now be described.

FIG. 9 illustrates the force applied by magnets 60 for deflecting power reed 58 incident to an initial potential

energy storing stroke for said reed and as related to the required force of said magnets for any subsequent deflections of the reed.

Assuming at the start that all power is off, the reed 58 would then have no deflection, as illustrated at ZERO DEFL. on the X coordinate. An initial momentary high current force of a magnitude to saturate magnets 60 for deflecting reed 58 sufficiently to close the initial gap G may be induced incident to the turning on of power or in any other suitable manner and is illustrated by the high current force line, which it will be noted is throughout always above or greater to the force line R representing the deflection requirement of reed 58. Immediately subsequent to the high current maximum force, indicated at F on the y axis, it is intended that maximum magnetic force on the magnets shall drop to a point F' on the chart. This reduced force, however, will maintain said magnets energized sufficient to hold reed 58 at its maximum deflection point +D. Thereafter, at any time, magnet 60 is caused to be deenergized reed 58 being released and by virtue of its inbuilt potential energy will move at its natural resonance to the point -D and immediately back to a point +D', as indicated by broken lines on the chart. At said point suitable well-known circuit control means, which include a one shot multivibrator OSM (FIG. 9A) will function to reenergize magnets 60, whereupon said magnets complete the final gap closing movement of reed 58 to the magnet, as represented by the solid line from point +D' to point +D on the chart. Now from the above and by observation of the chart, it will be noticed that the low current magnetic force curve will intercept the force line R, requirement for the reed at substantially the line +D' and will fall below the designed reed force R along a substantial portion of said line R. Thus the kinetic energy of the moving reed is being utilized during this time portion, and a reduced power is therefore possible for magnets 60 to return reed 58 the remaining short gap represented by line +D' to +D and restore full potential energy to said reed. Also, more latitude is permissible in the timing for reenergizing of said magnet.

FIG. 10 is a sinusoidal wave chart, relating the velocity curve of the reed 58 with a time displacement curve thereof and indicating the manner in which the reed becomes self cushioning in the printing oscillation thereof and how the shock, earlier described, is minimized in the operations of the reed. Also, FIG. 10 with FIG. 9A illustrates how the reed power means functions to operate the printing devices in a given time sequence with any input repetition rate from the master control devices.

Assuming that the magnet 60 is now energized, reed 58 will be held by said magnets at its maximum potential energy shown at +D on the y coordinate. The reed being stationary is so illustrated at zero velocity (ZERO VEL.) on the conjunction of coordinates xy. Upon release of reed 58 following a deenergizing of magnets 60, the reed advances to zero deflection point A on the reed displacement curve. At this time, the reed has attained maximum velocity as indicated on the velocity curve. Reed 58 now reverses its force as it moves beyond point A to point -D' during which the velocity curve will again go to zero. However, it will be recalled that the printing head 6 will continue in its forward printing stroke movement to effect a printing during this period movement of reed 58. Returning now from point -D', the reed curve recrosses the x axis at return maximum velocity and its force again is reversed in going to the point +D' at which point velocity will again be zero and all kinetic energy has now been translated to potential energy in reed 58.

It is recalled that at +D' reed 58 is not as yet fully returned to the magnets 60, indicated at point +D on the graphs. At this time, as earlier set forth, suitable one shot multivibrator time delay circuit means OSM (FIG. 9A) well known to the art, will cause a reenergizing of magnets 60 to complete the deflection of reed 58 from point +D' to point +D. It will be noted from the velocity

curve that during this short movement and time period the velocity of reed 58 produced by magnets 60 is so low that very little impact occurs as reed 58 strikes magnets 60 and thereby avoids noise and shock, with a possible breaking occurring to the tape 55.

Since any buildup time required in energizing magnets 60 are known, it of course, is possible to time its energizing action slightly early to the point +D' on the chart.

From the above description, it will be apparent that during any repetitious incoming signals spaced at a predetermined time interval, as from any suitable master control machine, magnets 60 are caused to be deenergized each time for releasing a power reed 58 to effect by said reed successive printing operations and that said magnets are timed by known circuit control devices to be reenergized in a timed sequence with such input signals so as to complete the restoring of potential energy again within reed 58 in corresponding time for each subsequent release thereof.

Suitable well-known feed back circuits, not herein deemed necessary to set forth, may be included where required to control timing starts for any input signal to the printer from the master control means.

While there has been shown a proffered embodiment of the invention, it will be understood that various changes may be made in the form, detail, arrangement and proportions of the parts without departing from the spirit and scope of the invention. Accordingly, it is intended that the foregoing disclosure be illustrative only and not limitative of the following claims.

I claim:

1. In a printer including print member means having characters thereon for impact printing; the combination therewith of;

means for storing potential energy including an oscillating reed which is deflectable to store potential energy therein;

means for holding said reed in a deflected position; means for rendering said holding means effective to hold said reed in the deflected position;

means interrelating said reed and said print member in such a manner that said print member is moved in response to movement of said reed and is capable of movement independently of said reed;

means for disabling said holding means to release said reed thereby causing said reed to utilize the potential energy stored therein acting through said interrelating means to propel said print member to perform a printing operation; and

said means for rendering said holding means effective is operable subsequent to said means for disabling said holding means to again hold said reed in a deflected position.

2. The invention according to claim 1; wherein said print member comprises a print head, said means for holding said reed comprises electromagnetic means,

said means for interrelating said reed and said print member comprises an operating train, and said reed in a continued movement will decelerate so that the print head continues onward freely thereof to perform a printing operation without transmitting an impact back into the operating train.

3. The invention according to claim 2; having an input control circuit adapted upon receiving an impulse signal to effect a deenergizing of said electromagnetic means; and

including a one shot multivibrator to effect a reenergizing of said electromagnetic means to accord with a return oscillation movement of said reed whereby to complete such return movement and to restore the initial potential energy therein.

4. The invention according to claim 3; said operating train including a pair of laterally spaced pulleys mounted for nondisplacement and a pulley

- intermediate thereof mounted for displacement with said printing head; and a flexible tape threaded successively around said pulleys and being fast at one end to said reed, with the opposite end of said tape secured against movement. 5
5. The invention according to claim 4; having a slideable member supporting said intermediate pulley for displacement therewith; resilient means yieldably connecting said member with said printing head; and 10 means biasing said slideable member to maintain tension on the tape and to effect return movement of said slide member and said printing head during a return oscillating movement of said reed.
6. The invention according to claim 5; and 15 a shiftable carriage including a rock frame pivoted thereon; said printing head mounted at its upper end for rotation in said rock frame; a step motor having a drive shaft forming universal 20 joint connection with the lower end of said printing head whereby said printing head is rockable with said frame in the said printing operations thereof; and wherein said pair of laterally spaced pulleys and said 25 slideable member with said intermediate pulley thereon are supported upon said carriage; and said flexible tape in cooperation with said pulleys will transmit movement of said reed for operating said rock frame and thereby said printing head in any 30 shifted position of said carriage.
7. The invention according to claim 6; and said printing head adapted of selective adjustment to alternative vertical positions for bringing one row or another row of circumferentially arranged printing characters thereon into active printing position. 35
8. The invention according to claim 7, including

a pair of opposed electromagnets supported upon said carriage; an armature pivoted upon said carriage to extend intermediate said magnets and having a distal end thereof engageable with the printing head; a pair of opposed springs connected to said armature for normally equally biasing the same in opposite directions; and wherein a simultaneous energizing of either magnet with a deenergizing of the other serves to effect said selective adjustment of the printing head; and wherein during such adjustment one spring is increased in tension while the other is decreased, whereby a more rapid release of said armature is effected from either energized magnet as the same becomes deenergized.
